UNITED STATES PATENT OFFICE.

JOHN H. JOHNSTON, OF NEW YORK, N. Y.

DESIGN FOR A SPOON.

SPECIFICATION forming part of Design No. 20,493, dated February 3, 1891.

Application filed December 29, 1890. Serial No. 376,130. Term of patent 7 years.

To all whom it may concern:

Be it known that I, JOHN H. JOHNSTON, a citizen of the United States, residing at New York city, State of New York, have invented 5 a certain new and ornamental Design for Spoons, of which the following is a description.

The design is represented in the accompanying drawing, which shows a spoon having a conventional bowl and stem or handle extending from it. On the end of the handle and constituting a prolongation of it is a statuette representation of Rip Van Winkle. This familiar character is represented standing with his left hand raised to his forehead, 10 a soft hat being upon his head and somewhat pushed back from his forehead. His beard is long, shaggy, and unkempt. His right hand grasps his gun just in front of the lock, and the barrel is to the front and pointed downward. His garments are ragged and worn. 15 On the handle of the spoon below the figure are the words "New York," in ornamental letters, the words being read downwardly with the handle of the spoon vertical. These letters are inconspicuous and not an essential 20 feature of the design. The end of the handle is formed with an ornamental scroll which forms the base on which the figure stands.

In the drawing, A represents the bowl of the spoon; B, the stem extending therefrom; 30 C, the figure of Rip Van Winkle, and at D the words "New York" are seen.

Further lettering of the design seems unnecessary, as its salient feature, the familiar figure of old Rip Van Winkle, needs no special description, and the general appearance and detail of the design are obvious from the accompanying drawing. 35

I claim as my invention and desire to secure by Letters Patent— 40

The design for spoons herein described and illustrated.

In witness whereof I have hereunto signed my name in the presence of two subscribing witnesses.

JOHN H. JOHNSTON.
